UNITED STATES PATENT OFFICE.

GREGOIRE POIRIER, OF GARFIELD, CLAY COUNTY, KANSAS.

DESIGN FOR A CHIMNEY-CAP.

SPECIFICATION forming part of Design No. 19,304, dated September 10, 1889.

Application filed June 24, 1889. Serial No. 315,433. Term of patent 14 years.

To all whom it may concern.

Be it known that I, GREGOIRE POIRIER, a citizen of the United States, residing in Garfield township, in the county of Clay and State of 5 Kansas, near Palmer, Washington county, Kansas, have invented certain new and useful Improvements in Designs for Chimney-Caps; and I do hereby declare the following to be a full, clear, and exact description of the invention, such as will enable others skilled in the art to which it appertains to make and use the same, reference being had to the accompanying drawings, and to the letters of reference marked thereon, which form a part of this 10 specification.

Figure 1 is a perspective view of the cap in position, and Fig. 2 a vertical section with ornament removed.

The leading features of my design consist 15 in a cover or top E, sides A, extending below the top course of brick, flange C around the

flue-opening, extending above and below said cover E, and an ornament B, secured to the top of the cap, leaving a space beneath, as shown, said cap, exclusive of the ornament, having 25 the appearance of being formed or cast of a single piece of material.

d d merely represent the lugs by means of which the ornament is secured to the cap.

What I claim is—

The design for a chimney-cap, consisting of the top or cover E, having sides A, flange C, and ornamental portion B, raised above the cover E, substantially as shown and described.

In testimony whereof I affix my signature in presence of two witnesses.

GREGOIRE POIRIER.

Witnesses:

WILLIAM DOCKING,
M. C. PORTER.
